WRITING INSTRUMENT

Henry Bovin, Danbury, and Grover H. Jensen, Woodbury, Conn., assignors to The B. F. Goodrich Company, New York, N.Y., a corporation of New York

Filed Apr. 29, 1968, Ser. No. 11,679

Term of patent 14 years

Int. Cl. D19—06

U.S. Cl. D74—17

FIG. 1 FIG. 2 FIG. 3 FIG. 6

FIGS. 1, 2 and 3 are side elevational views of a writing instrument showing our new design taken from three different positions;

FIG. 4 is a top plan view of the writing instrument;

FIG. 5 is a bottom plan view thereof; and

FIG. 6 is a side elevational view of the writing instrument in writing position.

We claim:

The ornamental design for a writing instrument, substantially as shown.

UNITED STATES PATENT OFFICE
CERTIFICATE OF CORRECTION

Design No. 218,491

August 18, 1970

Henry Bovin et al.

It is certified that error appears in the above identified patent and that said Letters Patent are hereby corrected as shown below:

In the heading to the printed specification, lines 4 and 5, "assignors to The B. F. Goodrich Company, New York, N. Y., a corporation of New York" should read -- assignors to Berol Corporation, Danbury, Conn., a corporation of Delaware --.

Signed and sealed this 16th day of March 1971.

(SEAL)
